[57] CLAIM

The ornamental design for a gun target, substantially as
shown and described.

DESCRIPTION

FIG. 1 is a front view of a gun target showing my new
design;

FIG. 2 is a front view of a second embodiment of the
gun target shown in FIG. 1 wherein the pattern of FIG.
1 is shown in duplicate, partially superimposed on one
another;

FIG. 3 is a front view of a third embodiment of the gun
target shown in FIG. 1 wherein four of the patterns of
FIG. 1 are partially superimposed on one another; and
FIG. 4 is a front view of a fourth embodiment of the
gun target shown in FIG. 1 wherein the target has five
sighting areas, each similar to the pattern shown in FIG.
1.

The gun target is of no substantial thickness and has a
planar surface.
